DESIGN FOR A LIQUID DISPENSING UNIT

Isaac J. Leavitt, Denver, Colo.

Application May 24, 1940, Serial No. 92,575

Term of patent 3½ years

To all whom it may concern:

Be it known that I, Isaac J. Leavitt, a citizen of the United States, residing at Denver, in the county of Denver and State of Colorado, have invented new, original, and ornamental Design for a Liquid Dispensing Unit, of which the following is a specification, reference being had to the accompanying drawing, forming part thereof.

Fig. 1 is a top plan view of a liquid dispensing unit, showing my design.

Fig. 2 is a front elevational view; and
Fig. 3 is an end elevational view thereof.

The rear of the dispensing unit is plain.

I claim:

The ornamental design for a liquid dispensing unit, as shown and described.

ISAAC J. LEAVITT.
